UNITED STATES PATENT OFFICE

168,322

DRESS

Myron I. Sterngold, New York, N. Y.

Application December 29, 1951, Serial No. 17,853

Term of patent 3½ years

(Cl. D3—26)

To all whom it may concern:

Be it known that I, Myron I. Sterngold, a citizen of the United States of America, residing in New York, county of New York, and State of New York, have invented a new, original, and ornamental Design for a Dress, of which the following is a specification, reference being had to the accompanying drawing, forming part thereof,

Fig. 1 is a front view of a dress with the wing or flap members drawn to the front and showing my new design;

Fig. 2 is a rear view of that shown in Fig. 1; while

Fig. 3 is a rear view of that shown in Fig. 1 with one wing or flap member drawn to the rear and the other in an extended position; and

Fig. 4 is a front view of that shown in Fig. 3 with both flap members drawn to the rear.

I claim:

The ornamental design for a dress, substantially as shown.

MYRON I. STERNGOLD.
